(57) CLAIM

The ornamental design for a dispenser for laundry use, as shown and described.

DESCRIPTION

FIG. 1 is a top, side perspective view of the dispenser for laundry use showing my new design;

FIG. 2 is a side elevation view, the dispenser being symmetrical; and,

FIG. 3 is a top plan view, the bottom view being a mirror image thereof.

1 Claim, 3 Drawing Sheets

FIG. 1

FIG. 3
